UNITED STATES PATENT OFFICE.

CLARENCE J. MUSSEHL, OF FORT ATKINSON, WISCONSIN, ASSIGNOR TO MUSSEHL AND WESTPHAL, OF FORT ATKINSON, WISCONSIN, A CORPORATION OF WISCONSIN.

DESIGN FOR A BAZOO.

Application filed March 3, 1925. Serial No. 12,554. Term of patent 3½ years.

To all whom it may concern:

Be it known that I, CLARENCE J. MUSSEHL, of Fort Atkinson, in the county of Jefferson and State of Wisconsin, have invented a new, original, and ornamental Design for Bazoo, of which the following is a specification, reference being had to the accompanying drawing, forming part thereof.

The drawing illustrates a plan view of the article, showing my new design.

I claim:

The ornamental design for a bazoo, as shown.

In testimony that I claim the foregoing I have hereunto set my hand at Fort Atkinson, in the county of Jefferson and State of Wisconsin.

CLARENCE J. MUSSEHL.
